[57] ABSTRACT

A hydraulic cushioning unit for railway cars includes a cylinder with a piston and piston rod assembly reciprocable therein and which during operation provides for the flow of fluid from a high pressure chamber through the piston rod to a low pressure reservoir. The reservoir is of a flexible boot type having one end connected to an intermediate cylinder head and its other end secured to a portion of the piston rod. Fluid from the high pressure chamber flows through the piston rod and outwardly through radial ports to the reservoir. A cylindrical deflector is positioned on the piston rod in the area of the ports and includes a plurality of openings or slots which are arranged to divide and deflect the hydraulic fluid into a plurality of dispersed streams providing a reduced velocity impact against the inner surface of the flexible boot.

BACKGROUND OF THE INVENTION

1. Field of the Invention

This invention concerns a hydraulic cushion unit of a type utilized in railway car application for dissipating forces occurring as a result of coupler impacts.

2. Description of the Prior Art

Cushioning units of the type to which the present invention pertains are disclosed in the William H. Peterson U.S. Pats.; No. 3,275,164 patented Sept. 27, 1966, and No. 3,334,757 patented Aug. 8, 1967.

SUMMARY

It is the primary object of the present invention to provide an improved hydraulic cushioning unit which includes an arrangement permitting the rapid discharge of a large volume of fluid into a flexible reservoir with the volume being dispersed in a multiplicity of streams in order to prevent possible damage to the flexible material of the reservoir. The primary objective is achieved by the utilization of a deflector which is attached around the outer peripheral surface of a piston rod, the deflector including a plurality of ports or slots through which hydraulic fluid is directed in widely dispersed streams to the interior of a flexible boot or reservoir. The multiplicity of slots provides for reduced velocity impingement on the inner surfaces of the reservoir. Further, the slots are disposed in an oblique fashion to prevent excessive pressure building up in confined areas of the flexible material which might cause possible ballooning or rupturing of the flexible reservoir.

BRIEF DESCRIPTION OF THE DRAWINGS

FIG. 1 is a cross-sectional view through an improved hydraulic cushioning unit;

FIG. 2 is an enlarged cross-sectional view of a portion of a piston rod deflector and flexible boot;

FIG. 3 is an enlarged elevational view of a deflector connected to a piston rod;

FIG. 4 is a cross-sectional view taken substantially along the line 4-4 of FIG. 3; and

FIG. 5 is a cross-sectional view taken substantially along the line 5-5 of FIG. 4.

DESCRIPTION OF THE PREFERRED EMBODIMENT

FIG. 1 discloses a hydraulic cushioning unit 10 comprising a cylinder 11 having an inner cylindrical wall surface 12 and an outer cylindrical surface 13. One end of the cylinder 11 is closed by means of a cylinder head 14 and the other end of the cylinder 11 is open as indicated at 15. A return spring 16 is suitably positioned around the outer cylindrical wall surface 13 and is

retained at one end by means of a retainer stop 17 and a slidable ring 18. The other end of the spring 16 is in engagement with a retainer stop 19 on the cylinder 13.

A metering pin 21 including suitable metering flutes

5 22 is rigidly connected to the head 14 and projects longitudinally within the cylinder 13. A piston 23 is positioned for reciprocation within the cylinder 11. The piston 23 is provided on one side with a pocket 24 having a metering valve plate 25 movably disposed therein. The valve plate 25 also includes a metering orifice 26 which cooperates with the metering pin 21 to provide for the flow of fluid from a high pressure chamber A on one side of the piston to a low pressure chamber B disposed on the other side of the piston. A threaded end portion 27 of a piston rod 28 is securely connected to the piston 23. The piston rod 28 includes a passageway or bore 29 which receives fluid from the high pressure chamber A and discharges the same through a plurality of radial ports 30. A plurality of converging bores 31 are also provided in the piston rod 28 and communicate with the passageway 29. The piston rod 28 also is provided at its end with an end plate 32.

15 25 An intermediate cylinder head 33 is positioned within the cylinder 11 and includes a longitudinal bore 34 communicating with a cavity 35. An apertured retainer plate 36 is disposed at one end of the cavity 35 by means of a snap ring 37. A movable valve element 38 is adapted to be moved over the bore 34 in one position to close the same.

20 35 30 A cylindrical boot protector 39 is suitably connected within the cylinder 11 to the intermediate cylinder head 33. The protector 39 is more specifically described in one of the aforementioned related patent applications. A flexible boot or hydraulic reservoir 40 has one end thereof connected at 41 to the cylinder head 33. The boot 40 is open at this end to provide for communication through the bore 34, cavity 35, with the low pressure chamber B. The said open end is indicated at 42 in FIG. 1. The other end of the boot is provided with a circumferential flange portion 43, as best shown in FIG. 2, and which is held on one side by 40 means of a stop ring 44 and a sleeve 45 suitably connected to the piston rod 28 to exert a clamping force on the ring 44 which in turn exerts a clamping force on the flange portion 43.

45 35 50 As best shown in FIGS. 3, 4, and 5, a deflector is designated at 46 and includes an outer cylindrical wall 48 provided at one end with a circumferentially extending shoulder 49. A plurality of circumferentially spaced spacer lips 50 are provided at the other end of the cylindrical wall 48 to space and support the deflector 55 50 about the cylindrical piston rod 28. The shoulder 49 is also provided with an inner circumferential surface or opening 47 which fits about the piston rod 28. The cylindrical wall 48 also includes a plurality of circumferentially and longitudinally spaced ports or slots 51 which may vary in size as indicated. The ports 51 include sloping wall portions 52 which slope in the direction indicated, i.e., obliquely outwardly. Ports 53 in the vicinity of the shoulder 49 slope in an opposite direction and include wall portions 54. As best shown in FIG. 5, the shoulder 49 also includes an annular undercut or flange 55. As best shown in FIGS. 1 and 2, the deflector 46 is positioned immediately in the area of

the ports or bores 30 formed in the piston rod 28. The deflector shoulder 49 is suitably welded to the exterior surface of the piston rod 28 and the flange 55 provides one side of a securing connection which receives the flexible flange portion 43 in clamping relation. Thus with the sleeve 45 exerting a continuing thrust on the ring 44 the boot end or flange 43 is tightly connected to the shoulder 49.

THE OPERATION

In the operation the cushion unit is suitably disposed at the end of a railway car and connected within the center sill so that upon an impact upon the coupler the cylinder head 14 and cylinder 11 are moved in the direction toward the end plate 32 which is rigidly secured to the center sill. This buff movement causes fluid to move from the chamber A through the metering orifice 26 into and through the passageway 29 and outwardly through the ports or openings 30. During this movement the valve plate 25 is in the position indicated in FIG. 1. Fluid now flows through the ports 30 and through the bores 31 outwardly from the passageway 29. The flow of fluid under high pressure through the ports 30 is deflected by means of the deflector 46 which divides high volume flow into a plurality of widely dispersed streams by means of the openings 51 and 53. Also fluid flows longitudinally outwardly between the spacer lips 50 into the flexible reservoir 40.

By the dispersion of fluid over a larger area of the flexible boot there is less likelihood of the reservoir ballooning at one end which can cause rupture or possible damage to the flexible material of the reservoir. The widely dispersed streams dissipate the fluid pressure over a much larger area and thus boot failure problems are greatly diminished. Further, the multiplicity of slots or openings reduces the impingement velocity against the reservoir inner wall. This results because of the greater area leading out of the annular space between the deflector and the piston rod. Fluid flows out of the ports 30 at a high velocity into this annular space and this velocity is reduced as it emerges from the ports 51. Thus the impact energy is dissipated and cushioning is achieved with full protection afforded by the deflector 46 of the flexible boot 40. After the cylinder 11 and piston 23 have closed the unit is returned to its original position shown in FIG. 1.

During the closing of the cylinder 11, suitable stops on the center sill of the railway car engage and hold the slideable ring 18 stationary so that the spring 16 is compressed and after the impact ceases the spring of course again returns the unit to its position shown in FIG. 1. During the return movement the valve plate 25 is displaced from the end of the passageway 29 so that a large quantity of fluid can return from the passageway 29 to the high pressure chamber A. The converging ports 31 during return movement are within the low pressure chamber B and fluid from the chamber B is returned through the ports 31 into the passageway and to the chamber A. During a draft impact or force which could occur while the piston 23 is disposed in a position between the intermediate head 33 and the end plate 14, the ports 31 would in effect supply a metering function momentarily reversing the fluid flow through ports 31. During said draft motion a limited amount of fluid

would flow between the circumferential surface of the piston 23 and the inner surface 12 of the cylinder 11. The tolerances are such that a limited clearance is provided between the piston 23, rings and cylinder wall 12 to permit such a limited flow. The aforesaid description of the operation during buff and draft impacts occur when a car or train is not in over-the-road operation, but is being made up. During over-the-road operation, the run-in and run-out, which is always present, cause continued reciprocation of the pistons and piston rods relative to the cylinders of each cushion unit. Thus these normal forces of operation and impact and draft control by the cushion unit provides for substantially constant flow of fluid through the deflector ports. Thus the deflector is effective to reduce the velocity forces assuring continued long life operation of the flexible reservoir.

Thus it is clear that the objective of the invention has been fully achieved by the provision of the deflector 46 which permits the large volume fluid to be widely dispersed and in a direction which will not cause damage to the flexible boot, cause ballooning or other undesirable effects.

What is claimed is:

1. In a hydraulic cushioning device for railway cars including:
  - a hydraulic cylinder including a first cylinder head adjacent one end thereof,
  - a second cylinder head disposed within said cylinder between an opposite open end of said cylinder and said first cylinder head, said second cylinder head having a longitudinal opening therethrough,
  - a piston slidably positioned between said cylinder heads and providing on one side of said piston a high pressure chamber,
  - a piston rod connected to said piston and positioned for sliding movement through said longitudinal opening,
  - said rod having a passageway,
  - metering means between said piston and said high pressure chamber providing for the metered flow of fluid from said chamber through said passageway during a buff impact,
  - a flexible tubular reservoir having an open end,
  - means sealingly connecting the other end of said tubular reservoir to said piston rod,
  - second means connecting the open end of said reservoir to said second cylinder head, to provide for communication between said reservoir through said longitudinal opening with a low pressure chamber disposed on an opposite side of said piston,
  - said piston rod having aperture means extending substantially radially to provide for the flow of fluid to said reservoir from said high pressure chamber during an impact, the improvement comprising:
  - a deflector including a sleeve having a cylindrical wall extending circumferentially around said piston rod,
  - said wall having a plurality of ports extending substantially radially for directing a plurality of dispersed streams of fluid from said passageway into said tubular reservoir the walls of said ports extending obliquely with respect to the longitudinal axis of said piston rod.
2. The invention in accordance with claim 1,

said ports comprising elongated slots with certain of
said walls of said slots extending obliquely in one
direction and certain others extending obliquely in
an opposite direction.
